[57] CLAIM

The ornamental design for a cargo net, as shown and described.

DESCRIPTION

FIG. 1 is a perspective view of the cargo net embodying the design of the present invention;

FIG. 2 is a front end elevational view thereof, the rear end being a mirror image of the front shown in FIG. 2;
FIG. 3 is a side elevational view thereof, the side opposite being a mirror image of the side shown in FIG. 3;
and,

FIG. 4 is a top plan view thereof, the bottom view being a mirror image of the top view shown in FIG. 4.

FIG. 1

FIG. 2

FIG. 3

FIG. 4
